SHOE VENTILATING DEVICE

Filed July 31, 1929

R.H. SCHWALM,
INVENTOR.

BY *William A. H. Cottle,*
ATTORNEY.

UNITED STATES PATENT OFFICE

RUDOLPH H. SCHWALM, OF MILLVALE, PENNSYLVANIA, ASSIGNOR OF ONE-HALF TO
LAVERNE C. KNIRNSCHILD, OF MILLVALE, PENNSYLVANIA

SHOE-VENTILATING DEVICE

Application filed July 31, 1929. Serial No. 382,372.

The present invention relates to devices for aerating and ventilating shoes, and provides a means comprising a bellows, with appropriately located valves, and an operating piston 5 adapted to be automatically operated in walking, and suitable conveyor and delivery tubes for distribution of the pumped air within the shoe, as will be described in detail as the description proceeds hereinafter.

10 Suitable means also provides for the supply of fresh air to the bellows, by means of an opening in the heel of the shoe, and a valve in the bottom of the said bellows, as will be described.

15 The actuation of the bellows for pumping fresh air into the interior of the shoe, comprises a novel piston, and recess, whereby the natural motion of the heel, as it contacts the ground in walking, operates the piston, which 20 in turn actuates the bellows to pump the air into the shoe, all of which will be fully described below.

Many of the parts, such as the non-return valves are novel and ingenious, as well as 25 some of the details of the delivery air tubes as will be seen from the description.

From which it is evident the prime purpose of the device in hand is to provide a means for thoroughly aerating and cooling 30 the interior parts of a shoe, and to give comfort to the feet specially in warm weather, and to accomplish such object by utilizing the natural contact of the shoe heel with the pavement in walking, and without any additional effort from the person using a shoe so equipped.

In the drawings I have shown a complete example of my invention, with modifications of some of the details thereof.

40 Figure 1 is a top plan view of my invention. Figure 2 is a central longitudinal section on line 2—2 of Figure 1, the heel being shown in side elevation therein.

45 Figure 3 is a top plan view of the heel portion of the device taken on line 3—3 of Figure 2.

Figure 4 is a vertical section of the heel, taken on line 4—4 of Figure 3, showing the 50 interior construction of the heel.

Figure 5 is a transverse section taken on line 5—5 of Figure 3.

Figure 6 is a longitudinal section of a valve and its connecting parts taken on line 2—2 of Figure 1.

55 Figure 7 is a longitudinal sectional detail of the bottom plate of the bellows with the attached parts, taken on line 4—4 of Figure 3.

Figure 8 is a partial transverse section of the heel taken on line 8—8 of Figure 3 60 illustrating an air inlet means used.

Figure 9 is a partial side elevation of the heel, taken from the right of Figure 8, and showing the same features as Figure 8.

65 In the drawings the numeral 1 indicates a shoe having the usual sole 2, with the "uppers" 3, and a special heel 4, the construction of which last named heel will be described and forms an essential part of the present invention.

70 The heel 4 comprises the following parts, to wit, 5 which is preferably of "rubber," and an interior chamber 6 which is formed therein. Within the chamber 6 is a bellows 7 having a number of parts as follows. 8 is composed of suitable pliable fabric, such as very thin canvas or the like, the upper and over-turned edge of which is indicated by the numerals 10, 10, said edge being complementary to the depression 11, formed in the upper 75 surface of the heel portion 12, and said edge 10 is placed immediately beneath the stiff leather plate 13 as shown clearly in Figures 3, 4 and 5.

80 The lower edge 14 of the wall 8 is secured to the bottom plate 15, which is preferably of light metal, such as aluminum, so the bottom of the bellows is stiff, and adapted to transmit the pushing action of the piston 16 to the resisting spring 17 as is at once understood. The shape in outline of this bottom bellows plate 15 is clearly shown by the dotted perimeter 18 in Figure 3. The extension 19 in Figures 3 and 4 it is noted extends into a small chamber 20 formed in the heel portion 5, extending from the chamber 6 before described. The purpose of this extension plate 19, is to engage the descending pin 21 as shown in Figure 4. Hingedly connected to the plate 15 is the piston 16, which recipro- 85

90

95

100

cates in the cavity 22, and has a preferably convex bottom surface 23, adapted to engage the surface of the pavement in walking.

Mounted on the upper surface of the plate 15, is a spiral spring 17, which is held in position by means of the bent plate 24, which is secured at 25 to said bottom plate 15. The upper end of the spiral spring 17 engages against the plate 13, and normally keeps the bellows 7 extended with its bottom plate 15 upon the floor of the chamber 6 (see Figure 4).

Mounted in the bottom bellows plate 15 is a small non-return valve 26, which admits air 15 to the interior of the bellows 7, from the chamber 6, but prevents a return flow thereto, as is at once understood. The nature of this non-return lower valve is understood from Figures 3 and 7, in which a small gutta- 20 percha hemisphere 27 is mounted in a complementary hemispherical holder 28, having several over-turned prongs 29, 29, as shown. There is a small vertical space between the bottom side of the prongs named, and the top 25 of the hemisphere 27, which when the plate 15 is suddenly lowered, permits the inrush of air through passage 30 to lift the hemisphere 27 off its seat, as is at once understood from Figure 7. However a reverse motion 30 of the plate 15 causes the hemisphere to seek its seat, and prevent a reverse flow of air through the passage 30.

Mounted in the upper plate 13, is another valve and its connecting parts, which I have 35 numbered 31, and in which as clearly shown in Figures 1 and 6 of the drawings, a small tubular casting 32 carries within the recess 33, a ball valve 35, and this valve is of the non-return type, as is readily understood from the 40 drawings, permitting air to pass from the bellows 7 into the disc-shaped chamber 36, but preventing a reverse flow of air, into the bellows. It will be noted that the disc-shaped casting 37 is slidably fitted into the tubular casting 32, so that the former may be readily 45 disengaged when desired.

The disc-shaped casting 37 is mounted in the inner-sole 38 by means of the extensions 39, 39, and its inner chamber 36 connects at 50 40 with the preferably rubber tube 41, which last is used as a connecting and conveying tube to the laterally distributing tube 42. It will be noted that at 43, 43, and at 44, 44, etc., distributing vent holes are placed to 55 permit air issuing from the tubes 41 and 42 to be distributed within the shoe cavity 45.

Another feature should be described, to wit, the means for providing unpolluted air to the bellows 7. In Figures 8 and 9 of the 60 drawings, the chamber 6 is shown, and leading therefrom is the fresh-air passage 46, which joins the cavity 47, which last by means of the perforations in the plate 48 has access to the outside air. The fresh air thus admitted to the chamber 6, gains admission

to the bellows through the valve 26, as the bottom plate 15 of the bellows is operated by the piston 16.

The over-turned edge 10, of the bellows 7 it will be noted is preferably cemented to the bottom face of the plate 13 in order to make an air-tight bellows, and the plate 13 is secured to the bottom part 5 of the heel 4 by nails or pins shown at 49, 49 as shown in Figure 3, as is at once understood. 75

The operation of the device, it is believed is apparent from the foregoing description of the parts, but will be briefly outlined as follows. As the person using the device walks along the pavement, the rear corner 50 of the heel 4 engages the pavement first, after which the rounded surface 23 of the piston 16 is depressed, and the bottom plate 15 of the bellows is pushed upward, air supplied by the fresh air inlet 46 is free to enter the valve 26 in said lower plate 15, and as the person lifts his foot the spring 17 causes the plate 15 to again seek the bottom of the chamber 6 thereby opening the valve 26, and air rushes into the bellows 7. As the said valve 26 is of the non-return type as before described, the air is held in the bellows until the person using the device again treads on the piston 16, which then causes a pressure in the bellows, as the bottom plate 15 rises and the air passes through the upper valve 31 into the disc-shaped chamber 36 of the casting 37. From there by the same impulse, the air is driven along the delivery tubes 41, and 42, where it is discharged through the perforations 43, 44, etc., into the chamber 45 of the shoe 1. 90

It will be noted also that by means of the extension 19 of the bottom bellows plate 15, same is in engagement with the pin 21, which acts somewhat like a fulcrum when the plate 15 is pushed upward by the piston 16, so the end 51 rises somewhat more than the end 19, as the extension 19 is loosely and slidably mounted on the pin 21, for this purpose. 100

The purpose of the non-return valve 31 it is believed is self-evident, so that as the bellows pumps the air into the delivery system of tubes, and the bottom plate 15 is lowered, the air so pumped will not be redrawn into the bellows. 110

It will be seen the piston 16 is provided with a cylindrical head portion 52, which neatly fits the cylindrical chamber 22, so no dirt, or at least very little grit can get into said chamber 22, and thus interfere with the slidable motion or reciprocation of the piston. This cylindrical head portion 52 it will be observed, is made of proper vertical depth, so the upper edge 53 of the piston head 54 is always above the bottom face 55 of the shoe heel 4, and thus dirt is prevented from getting into the chamber 22. 120

From the above description it is seen that I have provided a complete and ingenious device for the purpose intended, to wit, to cool 125

and ventilate the feet, in the natural course of a person's stride in walking, and without the slightest additional effort over that which one would ordinarily use.

5 I claim:—

1. In a ventilating and cooling device for shoes, a shoe having a sole and an interior chamber, a shoe heel having a chamber formed therein, a bellows having a rigid bottom, and upper plate, a spring mounted on the bottom plate adapted to normally hold the bellows in extended position, a hinged piston mounted on the bottom bellows plate, a cylindrical piston chamber in the heel, in 10 which the piston slidably reciprocates, a fresh air duct in the heel, an inlet valve mounted in the bottom bellows plate, an outlet valve mounted in the top plate of the bellows, and means connected to the said outlet valve for 15 conveying and distributing the air pumped by the bellows to the interior cavity of the shoe.

2. In a cooling device for shoes, a shoe provided with a sole and an interior chamber for 20 the foot, a shoe heel mounted on the shoe sole, having means for automatically pumping air using the walking action of the person to actuate the pumping means, and a conveying and distributing means comprising, a 25 disc-shaped casting, slidably mounted on the pumping means, and a longitudinal conveying tube having distributing air perforations therein, and a transverse distributing tube having distributing air perforations formed 30 therein, for cooling the interior chamber of the shoe.

3. In a cooling and ventilating device for shoes, an air distributing and conveying means, comprising a disc-shaped casting, 40 having a similar shaped chamber of vertically shallow dimensions formed therein, a downwardly extending tube leading from the chamber, and a lateral tube extending from the casting and connected with the casting 45 chamber, and a pair of prongs on the casting adapted to mount the casting in the material of the inner sole of a shoe.

4. In a shoe ventilating device, an inner sole, a disc-shaped casting having an inner 50 chamber, a downwardly extending air passage leading therefrom, and a lateral air passage leading from the said chamber, a pair of extensions adapted to attach the disc-shaped casting to the body material of the inner sole, a conveying and air distribution tube having a number of perforations in its surface, adapted to be embedded in the material of the inner sole, and of substantially the same diameter as the thickness of the inner sole, connected to the lateral passage of the aforesaid casting, and a transverse air tube connected with the first-named tube, having closed ends and a number of perforations in its surface, for distributing the air received 55 from the conveying and air distributing tube.

5. In a shoe ventilating means, a heel having a bellows chamber formed therein, a bellows having a bottom and an upper plate, a spring for normally holding the bellows plates in relatively extended positions, a piston chamber in the heel, a hinged piston on the bottom plate adapted to reciprocate in the piston chamber, a fresh air duct and screened opening in the side of the heel, and an inlet and an outlet valve mounted in the bottom and upper bellows plates respectively. 70

6. In a shoe ventilating means, a heel having a bellows chamber formed therein, an extension plate chamber adjacent thereto, 80 and a cylindrical piston chamber, a bellows having a bottom plate and an upper plate, an extension on the bottom plate adapted to complementarily fit the aforesaid extension plate chamber, and provided with an aperture near its outer end, extensible means tending to normally hold the two bellows plates in extended positions, a hingedly connected piston on the bottom plate, an enlarged head on the piston having a rounded bottom, and cylindrical sides, adapted to slidably engage the walls of the piston chamber, an inlet and an outlet valve carried on the bottom and upper plates respectively of the bellows, and a pin passing vertically through the upper plate, the bottom plate extension and the lower portion of the heel, and on which the bottom bellows plate is designed to reciprocate when the piston is properly actuated. 85

7. In a shoe ventilating device, a heel having a bellows provided with a bottom and a top plate, an inlet and an outlet valve, a piston chamber formed in the heel, a piston hingedly connected to the bottom plate of the bellows, a piston head of complementary shape to the piston chamber, having a rounded head protruding beneath the heel, and vertical sides of sufficient vertical length as to prevent the upper surface of the piston head protruding beyond the lower end of the piston chamber, for preventing grit or similar débris reaching the interior of the piston chamber. 100

In testimony whereof I affix my signature. 105
